UNITED STATES PATENT OFFICE

135,924

DESIGN FOR A COMPACT OR SIMILAR ARTICLE

Harry Morris, Chicago, Ill.

Application April 5, 1943, Serial No. 109,905

Term of patent 14 years

To all whom it may concern:

Be it known that I, Harry Morris, a citizen of the United States, residing in Chicago, in the county of Cook and State of Illinois, have invented a new, original, and ornamental Design for a Compact or Similar Article, of which the following is a specification, reference being had to the accompanying drawing, forming part thereof.

Fig. 1 is an elevational view of the sides of a compact or similar article showing my design,

Fig. 2 is the inner view of the compact shown in Fig. 1, and

Fig. 3 is the edge view thereof in closed position.

I claim:

The ornamental design for a compact or similar article, substantially as shown.

HARRY MORRIS.
